United States Patent Office.

DAVID J. BRADY, OF GREENWICH TOWNSHIP, OHIO.

Letters Patent No. 90,989, dated June 8, 1869.

IMPROVEMENT IN COUPLINGS FOR WHIFFLETREES.

The Schedule referred to in these Letters Patent and making part of the same.

To all whom it may concern:

Be it known that I, DAVID J. BRADY, of Greenwich township, Huron county, and State of Ohio, have invented a new and improved Compound Clevis; and I hereby declare the following to be a full, clear, and exact description thereof, which will enable those skilled in the art to make and use the same, reference being had to the accompanying drawings, making a part of this specification, in which—

Figure 1 is a side elevation.

Figure 2 is an end view.

Similar letters of reference indicate corresponding parts.

My invention relates to couplings for the double and single-trees of carriages and other vehicles; and

It consists of a compound clevis, constructed and arranged with reference to the double and single-trees, as will be hereinafter more fully described.

A, in the drawings, is the body of my compound clevis.

It is made of iron, or of any suitable material, and is formed by uniting two single clevises, as shown at A' in the drawings.

B and C are bolts, which pass through openings in the rear and front arms of the clevis, near their outer extremities.

B' and C' are screw-nuts, by means of which the bolts B and C are secured in position.

The operation of my invention is as follows:

Having passed the bolt C through the end of the upper rear arm of the compound clevis into and through a suitable vertical opening in the double-tree, and finally through the lower rear arm of the clevis, secure it in position by means of the screw-nut C'.

In like manner, the bolt B is passed through the upper front arm of the clevis, thence through a vertical opening in the centre of the single-tree, and into and through the lower front arm, where it is secured in the same way as bolt C.

The remaining single-tree is adjusted, with reference to the double-tree, as the one just described.

When this is accomplished, the double and single-trees will have become connected together, and the usefulness of my invention will be apparent as soon as the draught is applied.

From the foregoing description, it is evident that the single-trees are brought forward and elevated so as to bring the draught upon the double-trees in nearly a direct line; that the strain which is usually exerted upon the bearings of the single and double-trees is, to a great extent, avoided; that it is very cheap in its construction, and highly ornamental.

Having thus described my invention,

What I claim as new, and desire to secure by Letters Patent, is—

A compound clevis, when used for uniting double and single-trees, constructed substantially as has been shown and described.

In testimony whereof, I have signed my name to this specification, in the presence of three subscribing witnesses.

DAVID J. BRADY.
